(57) **CLAIM**

The ornamental design for an ear irrigation device, as shown and described.

DESCRIPTION

FIG. 1 is a front, right and top perspective view of an ear irrigation device, showing our design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view of the ear irrigation device in another state.

(Continued)

The broken lines depict portions of the ear irrigation device that form no part of the claimed design.

1 Claim, 9 Drawing Sheets
